THOMAS LEACH, OF TAUNTON, MASSACHUSETTS, ASSIGNOR TO REED AND BARTON.

Letters Patent No. 80,748, dated August 4, 1868.

IMPROVED ICE-PITCHER.

The Schedule referred to in these Letters Patent and making part of the same.

TO ALL WHOM IT MAY CONCERN:

Be it known that I, THOMAS LEACH, of Taunton, in the county of Bristol, and State of Massachusetts, have invented a new and improved Ice-Pitcher; and I do hereby declare that the following is a full, clear, and exact description of the construction and operation of the same, reference being had to the accompanying drawings, making a part of this specification, in which—

Figure 1 is a vertical section.

Figure 2, a horizontal section.

In this invention a detachable and removable lining, of glass, china, or earthenware is employed, and in connection with it a combined valve and filter of peculiar construction, together with a novel and convenient device for holding the lining firmly in the pitcher, and at the same time preventing it from fracture by the sliding of the ice.

Hitherto ice-pitchers have been made either without any lining at all or with double walls, so attached together that the inner one cannot be readily removed, but constitutes a permanent part of the pitcher. Perhaps, in one or two instances, a pitcher has been constructed having a removable lining or inner wall, but in that case such wall was made of metal, and it has been foraminated for the purpose of allowing the water to flow freely through it.

My invention is entirely unlike any of these, being confined to a removable lining or inner wall of glass, earthenware, or chinaware, with the accompanying improvements above referred to, when constructed as I will now proceed to set forth.

In the drawings, A is the metallic outer wall of the pitcher, B its cover, C its handle, and D its nose. To the bottom of this pitcher, on the inside, is firmly attached a ring or flange, E, of the same metal, and having several openings, $\alpha\alpha$, so that the air shall freely pass around the ring, and to and from the space within it.

Inside of this pitcher I set another pitcher, F, composed of glass, earthenware, or chinaware, and so constructed as to rest firmly upon the ring E at the bottom, and to fit around its top at $\alpha\alpha$, accurately against the outer walls of the pitcher at their top, leaving a uniform air-space around the sides and under the bottom of the glass lining or inner wall.

G is a ring, of plated metal or silver, which fits down upon the top of the glass, for the purpose of confining it in position, being provided with a flange, g, all around its inner edge, which projects down inside of and almost or quite in contact with the glass lining, and completely protects the upper edge of the glass or other material of which the lining is made from being broken by the ice sliding forward when the pitcher is inclined. This ring is provided with a widened or expanded lip, L, which covers the greater portion of the nose of the glass lining, leaving a space, however, at its end, for the water to flow out through.

Under this lip is a filter or screen, H, and inclined foraminated plate of metal, attached at its upper edge to the inner edge of the lip, and fitting closely to the lower part of the nose or spout of the glass lining. A flange, i, extends around this filter on its upper side, forming, in conjunction with it, a kind of box having a foraminated bottom. This box is covered and closed by a lid or valve, J, of plated metal, hinged just under the lip L, at the upper edge of the screen or filter.

The valve opens upward by the pressure of the water when the pitcher is inclined, and shuts down again, by its own weight, when the pitcher is placed erect. The ring, filter, and valve are thus all connected together, forming one piece, which can be readily inserted or removed when the lid of the pitcher is raised. When in place, it is confined there securely by means of a screw-rod, r, passing through it horizontally, and through two lugs on the side of the wall A or the nose D, at the upper edge thereof. A ridge may be raised across the lip L, at the suitable point, to conceal the screw-rod, and give the ring a neater appearance.

One of the great objects of this invention is to preserve the ice and prevent its melting as long as possible, thereby saving the material and making the supply of cold water more constant and unfailing. This it does to

a remarkable degree, preserving the same quantity of ice, under the same circumstances as other pitchers, as has been ascertained by careful experiment, at least twenty per cent. longer, in consequence of the non-conducting quality of the glass, and the fact of its being protected by the outside wall.

Another great object is to check, or entirely prevent, the condensation of moisture from the air upon the outer walls of the pitcher. The ice, being placed in the inner pitcher, and the latter being made of glass, or other similar non-conductor of heat, the outer wall A will remain all the while comparatively warm, and scarcely any condensation will take place upon it, leaving it neat and dry under almost all circumstances. The difference, in this respect, between my improved pitcher and those which have an inner lining of metal, is very great.

In the third place, the inner pitcher can be readily removed, if desired, and the outer wall A will then form a handsome pitcher of the usual form and construction. If, therefore, by any accident, the glass lining should be broken, it does not destroy the pitcher, or prevent its being used all the while.

I design manufacturing the pitchers of certain definite sizes and shapes, to be numbered, so that when the lining of one is broken, the owner need only order a lining of such a number, without sending the pitcher to be fitted with a lining, as heretofore.

The pitcher can be readily cleaned in all its parts, as will be seen from what has already been stated. The ring, filter, and valve can always be kept in the neatest order. No dirt from the ice or water can insinuate itself under or around the glass. It is difficult to conceive of any method of construction which will render it possible to produce a neater and more cleanly article of the kind than that above described.

Having thus described my invention, I do not wish to limit myself to the precise details of construction herein set forth, and particularly to the ring or circular plate for holding the glass lining in place, for other devices, similar in general principles, but different in construction, might, perhaps, be employed for the same purpose, to wit, holding the glass in place and protecting it from fracture; but

What I claim as my invention, and desire to secure by Letters Patent, is—

1. The combination of a detachable and removable glass, earthenware, or chinaware lining, or interior pitcher, with the metallic pitcher A, and a ring, plate, or other equivalent device for holding the pitcher and lining together, and yet permitting the lining to be removed when necessary.
2. The ring G, having the rim or flange g, when used in connection with the walls A and the lining F, in the manner and for the purpose set forth.
3. The combination of the ring G, filter II, and valve J, forming a neat attachable and removable apparatus for ice-pitchers, substantially as set forth.
4. The combination of the apparatus above referred to with the wall A and the screw-rod r, substantially as described.

THOMAS LEACH.
